CLAIM

The ornamental design for a probe for measuring electrical characteristics, as shown and described.

DESCRIPTION

FIG. 1 is a perspective view of a probe for measuring electrical characteristics showing my new design;

FIG. 2 is a front view thereof, the rear view being a mirror image thereof;

FIG. 3 is a right side view thereof, the left side view being a mirror image thereof;

FIG. 4 is a top view thereof;

FIG. 5 is a bottom view thereof;

FIG. 6 is a cross-sectional view thereof taken along line 6-6 in FIG. 2;

FIG. 7 is an enlarged cross-sectional view thereof taken along line 7-7 in FIG. 2; and,

FIG. 8 is an enlarged cross-sectional view thereof taken along line 8-8 in FIG. 2.

The dashed broken lines illustrate portions of the probe for measuring electrical characteristics that form no part of the claimed design. The dot-dash broken lines define boundaries of the claimed design and form no part thereof.
